MACHINE FOR MAKING SPRING MAT-
TRESSES AND THE LIKEPaul Sappington, Los Angeles, Calif., assignor of
one-half to J. C. Rosenthal, Los Angeles, Calif.

Application May 21, 1937, Serial No. 144,056

2 Claims. (Cl. 140—3)

This invention relates to a simple and efficient machine for use in joining the coiled springs of a mattress or similar structure, one of the objects being to provide a mechanism whereby elongated coiled springs can be fed to upstanding springs arranged in rows so as to become intertwined therewith and constitute resilient connections between them.

A further object is to provide a machine of this character which can be operated by one person and, when in action, will feed one or more coiled springs to the cushioning springs to be joined thereby.

A further object is to provide simple and efficient means for shifting the driving mechanism whereby the feed can be reversed at will so as to quickly reset it for successive operations.

A still further object is to provide a light machine of this type which will not readily get out of order and can be installed readily.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred form of the invention has been shown.

In said drawings

Figure 1 is a front elevation of the machine.

Figure 2 is a plan view thereof.

Figure 3 is a section on line 3—3, Figure 1.

Figure 4 is a section on line 4—4, Figure 3.

Figure 5 is a section through a portion of the machine taken on line 5—5, Figure 3, the motor being indicated by broken lines.

Figure 6 is a section through a portion of the machine taken on line 6—6, Figure 4.

Figure 7 is a section on line 7—7, Figure 1.

Figure 8 is an enlarged plan view of one of the grippers and its supporting head.

Figure 9 is a section on line 9—9, Figure 8.

Figure 10 is a plan view showing, in diagram, the relative positions of some of the cushioning springs and connecting coils.

Referring to the figures by characters of reference 1 designates the legs of a table 2 on which are mounted parallel strips 3 each having a row of upwardly extending pins 4. Longitudinal side rails 5 connect the legs and the entire supporting structure of the top 2 can be reenforced by means of braces 6 located wherever found desirable.

The rails 5 constitute a track on which are mounted wheels 7 connected to and supporting opposed portions of a carriage 8 which is in the nature of a yoke extending downwardly between the rails of the track.

The carriage is provided with a standard 9 in which is secured one end portion of a tubular housing 10 supported between its ends by a grooved roller 11 carried by a transverse shaft 12 which is supported by the legs at one end of 10 the machine.

The tubular housing 10 is held against rotation and the outer end thereof, which is the end farthest removed from the standard 9, has a hollow head 13 fixedly mounted thereon and 15 extending upwardly therefrom. A removable cover plate 14 is secured in any suitable manner to this head and is provided with bearing sleeves 15 in each of which is journaled a short shaft 16.

A drive shaft 17 is journaled within the tubular housing 10 and projects from both ends thereof. By means of chain and sprocket mechanism indicated generally at 18 and located in the head 13, rotary motion is transmitted from shaft 17 to the short shaft 16 so that they will all rotate 25 in the same direction simultaneously. The outer ends of the short shaft 16 which are extended toward the carriage 8, are provided with grippers indicated in detail in Figures 8 and 9. Each of these grippers includes a stationary finger 19 30 which is lapped by a clamping plate 20 having a tapered gripping end 21 slightly spaced from the finger 19 so as to provide a clearance 22 for the reception of the end convolution of a coiled spring to be actuated. It is to be understood that different types of gripping devices can be used and the particular construction of the one herein shown therefore is of no particular importance.

That end of shaft 17 adjacent to the standard 9 is provided with a friction wheel 23 normally engaged by a small friction wheel 24 on the shaft 25 of an electric motor 26. This motor has base members 27 and 28 and from the member 28 extends a depending ear 29 pivotally supported on a pin 30 located under the carriage 8. This 45 depending ear 29 is preferably made integral with a block 31 arranged beneath and fixedly secured to the base member 28 of the motor. To this same block is pivotally attached the lower end of an upwardly extended angular lever 32 carrying a friction wheel 33 at its upper end and extending laterally from this upper end of the lever 32 is an arm 34 in which is fixedly mounted the lower end of a bearing pin 35 carrying an anti-friction roller 36. This roller thrusts outwardly 50

55

or forwardly against an actuating rail 37 supported by depending arms 38 pivotally mounted under the top 2 adjacent to the ends thereof. Extending from the upper or pivoted ends of the arms are levers 39 connected by rods 40 to brackets 41 fastened to the end portions of a treddle 42. This treddle is extended longitudinally of the machine adjacent to the bottom thereof and is pivotally supported at its ends as shown at 43. The brackets 41 are so located that when the forward portion of the treddle is depressed, these brackets will be moved upwardly, thereby transmitting thrust to the rods 40 to the levers 39 and causing arms 38 to swing the rail 37 inwardly or backwardly so as to correspondingly move the anti-friction roller 36 wherever it may be located along said rail.

A lifting plate 44 is located below the base portion 27 of the motor and has a downturned bearing portion lifting upon the bottom of the carriage 8 and seated in a notch in said bottom as indicated by dotted lines at 46 in Figure 6. This lifting plate is provided with an upwardly extended finger 47. A connecting rod 48 is pivotally connected to the lever 32 and extends loosely through finger 47, there being a nut or other suitable stop device on this rod as indicated at 49 so as to prevent withdrawal of the rod from the finger when pulled in one direction.

30 A spring 50 is connected to the free end portion of the arm 34 and to the block 31 and thus serves to exert a constant pull upon arm 34 so as to hold friction wheel 33 normally spaced from the wheel 23 as shown in Figure 4. The spring 35 also serves normally to pull through lever 32 and rod 48 upon finger 47 with the result that the plate 44 thus presses upwardly against the base portion 27 of the motor so that the friction wheel 24 is normally in engagement with the friction 40 wheel 23.

With the parts arranged in their normal positions as described and as illustrated in Figure 4, the operator pulls on the head 13 so as to move the carriage 8 toward one side of the machine, the wheels 7 travelling along the rails 5 while the wheel 36 travels along the rail 37. The cushioning springs S to be joined are placed in upstanding positions on the pins 4 so as thus to occupy parallel rows on the strips 3 above top 2. 45 The long coiled springs C used for connecting the upper and lower convolutions of the upstanding springs are then placed with one end gripped tightly by the fingers 19 and 21 while the other end of these springs is placed in engagement 50 with the upper and lower convolutions of the nearest springs S in the parallel series. With the parts thus arranged the motor 26 is started and motion will be transmitted therefrom through the wheels 24 and 23 to shaft 17 which, 55 in turn, will transmit motion through the chain and sprocket mechanism to the shaft 16 and the grippers carried thereby. Consequently the two coiled springs which are to be entwined with the upstanding cushioning springs will be rotated and as a result of their helical configuration, they will feed forwardly automatically, passing 60 from one spring to another and not only becoming intertwined with the springs of each series but also with the corresponding springs of the opposed series so that following the complete advance of the two coiled springs being fed into the machine, the springs of each row will be joined together and will also be joined to the 65 springs of the other row, the connecting means

being the coiled springs C which were fed thereto by the advancement of the head 13.

If at any time during the forward feeding of the springs, it should be found desirable to retract them for the purpose of directing the same into proper engagement with the upstanding or cushioning springs, it becomes necessary merely for the operator to depress the treddle 42. This will cause an upthrust through rod 40 and lever 39 to arms 38 and rail 37 therefore will push 10 against the anti-friction roller 36 and cause lever 32 to swing to the left in Figure 4. Finger 47 will be released for swinging movement because the stop 49 will move away from it and as the plate 44 is supporting a part of the weight of the 15 motor, this weight will be sufficient to cause the motor to swing downwardly when finger 47 is released, thereby withdrawing wheel 24 from contact with wheel 23. During this operation wheel 33 which has been moving with lever 32, 20 will come into contact with both of the wheels 23 and 24. Consequently the rotation of shaft 17 will be reversed and the grippers, together with the springs engaged thereby, will also be rotated in a reverse direction so that the springs will be 25 unwound from the upstanding supporting springs on the pins 4 until the free ends of these connecting springs are brought to predetermined positions. By then releasing treddle 42 all of 30 the parts will be returned to their normal positions and the connecting springs can again be fed forwardly.

Following the complete seating of the connecting springs the grippers can be detached therefrom and the operator, by pulling on the 35 head 13, can move the carriage back to its initial position whereupon additional connecting springs can be attached to the grippers. Those springs on the pins which had been joined by the completed operation, can then be moved laterally to 40 allow the arrangement of another row of springs on one set of the pins 4. Therefore when additional connecting springs are fed by the machine, these newly applied springs on pins 4 will be joined to one row of springs of the partly 45 completed mattress. This operation can be repeated until a mattress or cushioning structure of any desired width has been produced.

Obviously the operator, while standing in front of the machine, can reach readily to any part of 50 the top and can also readily reach the head 13 for the purpose of moving it backwardly or forwardly as necessary. The operator is also located where he can easily guide the connecting springs as they are threaded forwardly into engagement with the parallel series of springs on the pins.

It is to be understood that movement of the carriage in one direction can be limited by a stop such as indicated at 50 in Figure 1.

What is claimed is:

1. A machine for forming a mattress of rows of cushioning springs joined by connecting springs, said machine including a structure for supporting parallel rows of cushioning springs, a carriage mounted for back and forth movement on said structure, and means operating independently of the carriage for rotating a connecting spring, said means including a motor, gripping means, reversible friction gearing for transmitting motion from the motor to the gripping means, and means under the control of the operator for shifting the friction gearing into reverse while the carriage is in any position within the structure.

2. The combination with a supporting structure, a top thereon, and upstanding rows of pins on the top, of a track carried by said structure, a carriage mounted for free movement therealong,
5 a tubular housing fixedly joined to the carriage and extending beyond one end of the top, a head carried by the housing and supported thereby beyond one end of the top, a gripper mounted for rotation relative to the head, a motor suitably
10 mounted on the carriage, a driving wheel there-
- on, a shaft in the housing, means driven thereby by actuating the gripper, a friction wheel on the shaft, an intermediate wheel, a rail mounted for swinging motion, means under the control of an operator for actuating the rail, and means movable along the rail for simultaneously tilting the motor and shifting the intermediate wheel to drive the shaft in either direction. 5
